Andrew Z. McBride

UNITED STATES PATENT OFFICE.

A. Z. McBRIDE, OF STEWART COUNTY, GEORGIA.

IMPROVEMENT IN COTTON-PRESSES.

Specification forming part of Letters Patent No. 31,323, dated February 5, 1861.

To all whom it may concern:

Be it known that I, ANDREW Z. McBRIDE, in the county of Stewart and State of Georgia, have invented a new and useful Improvement on a Machine for Packing Cotton; and I do hereby declare that the following is a full, clear, and exact description of the construction and operation of the same, reference being had to the annexed drawings, making a part of this specification, in which—

Figure 1 is a perspective view of one of the cotton-boxes. Fig. 2 is another box. Fig. 3 stands immediately over the third box. Fig. 4 represents the fourth box, over which it is placed. Figs. 5 and 6 are short posts at the ends of the boxes. Figs. 7 and 8 are views of four upright posts supporting the cap-piece, through which the screw passes. Figs. 10 and 11 represent the two follow-blocks. Fig. 13 is a cap or top piece supported by the four posts shown by Figs. 7 and 8. Figs. 15 and 16 show a view of the lever, which is placed on the top of the cap-piece.

To enable others skilled in the art to make and use my invention, I will proceed to describe its construction and operation.

I construct my cotton-press in any of the

known forms, first, by having two hewn sills placed at the bottom for a foundation. At or near the end of these two sills there are posts standing upright and securing the ends of each box, four extending upward to a sufficient height to support the cap-piece, through which the screw passes. Above in the center there is a stationary post, on which the screw stands and revolves when turned by the lever. The screw is of wrought-iron or cast, and also the tap, the tap being of a horizontal form extending downward, and at the ends of the arms the follow-blocks are fastened, so that when the screw revolves the tap moves up or down, thus forcing the follow-blocks in or out of the boxes.

What I claim as my invention, and desire to secure by Letters Patent, is—

The combination of the screw and tap A with its follow-blocks 10 and 11, when constructed and operated substantially as described.

A. Z. McBRIDE.
mark.
